United States Patent Office.

THEODORE W. RYDING, OF TULLY, NEW YORK.

Letters Patent No. 95,937, dated October 19, 1869.

IMPROVEMENT IN BUTTER-PACKAGES.

The Schedule referred to in these Letters Patent and making part of the same.

To all whom it may concern:

Be it known that I, THEODORE W. RYDING, of Tully, in the county of Onondaga, and State of New York, have invented a new and useful Improvement in Butter-Packages; and I do hereby declare that the following is a full, clear, and exact description thereof, which will enable those skilled in the art to make and use the same, reference being had to the accompanying drawings, forming part of this specification, in which—

Figure 1 is a sectional side view or elevation, and Figure 2 is a plan view.

Similar letters of reference indicate like parts.

This invention relates to certain improvements in butter-tubs, firkins, &c., whereby the head of the package is secured, liquid-tight, in a simple and accessible manner, as hereinafter more fully explained.

In the accompanying drawings—

A is the tub;

B is the head;

C is the cross-head; and

D D are the clamping-screws.

I construct my tub with a groove in its upper edge, and fill said groove with a packing, *a*, of rubber, or other suitable material. The head B is then placed over the end of the tub and clamped down firmly by a strong cross-head, C, and clamping-screws D d D d.

By these means the head is closed water and air-tight, and the tub can be stowed, bottom up, so that the brine will work from the bottom to the top of the package, and not leak out, and the butter kept sweet and good, and without liability of being damaged or spoiled.

The package is very accessible, and can be opened and again closed, air-tight, with very little trouble.

The cross-head C is made thick in its central part, so that the clamping-screws D d D d are protected from

injury when the packages are stowed or piled on top of each other; and they can be placed on their heads or tumbled about without said screws being damaged.

The ends of the cross-head are also rounded, as shown in fig. 2, so that the package can be rolled as ordinarily.

The screw-bolts D are mainly secured to the upper hoop *e*, and this not only secures the hoop in place, but if the staves become slack, the screws force the hoop further on to the tub and keep all tight.

The iron fittings are of cast malleable iron, and are provided at a light expense, the whole making a very convenient and reliable package.

I do not claim broadly the use of screws and nuts for securing the covers of fruit-jars and other vessels, as I am aware that this is not new; neither do I claim attaching the fastening-screws to a hoop, band, or collar encircling the vessel, as this has been done prior to the date of my invention; but having thus described my invention,

What I claim as new, and desire to secure by Letters Patent, is—

The improved butter-package, herein described, as a new article of manufacture, the same consisting of a tub, A, with packing-groove *a*, the cover B, cross-piece C, screws D, riveted to the tub and to the hoop *e* of the tub, and the nuts *d d*, when the cross-piece has its ends cut away, so that the screws and nuts do not project, all the parts being constructed and arranged substantially as herein described.

The above specification of my invention signed by me, this 12th day of June, 1869.

THEODORE W. RYDING.
